(57) **CLAIM**

The ornamental design for a deep well socket for engaging a tee fitting, as shown and described.

DESCRIPTION

FIG. 1 is a perspective view of my deep well socket for engaging a tee fitting showing my new design;

FIG. 2 is another perspective view of FIG. 1 thereof;

FIG. 3 is a front elevation view of FIG. 1 thereof;

FIG. 4 is a left side elevation view of FIG. 1 thereof;

FIG. 5 is a rear elevation view of FIG. 1 thereof;

FIG. 6 is a right side elevation view of FIG. 1 thereof;

FIG. 7 is a top plan view of FIG. 1 thereof; and,

FIG. 8 is a bottom plan view of FIG. 1 thereof.

It is certified that error appears in the above-identified patent and that said Letters Patent is hereby corrected as shown below:

The Title Page showing an illustrative figure, should be deleted and substitute
therefore the attached title page.

The sheets of drawings consisting of figures 1-8, should be deleted to appear as per
attached figures 1-8.

Signed and Sealed this
Nineteenth Day of April, 2011

David J. Kappos
Director of the United States Patent and Trademark Office
